United States Patent Office

Des. 185,502

Patented June 16, 1959

185,502

BOWLING SCORE CABINET

Jerry C. Koci, Barrington, Ill., assignor to Chicago Dynamics Industries, Inc., Chicago, Ill., a corporation of Illinois

Application February 19, 1958, Serial No. 49,699

Term of patent 14 years

(Cl. D33—19)

Fig. 1 is a perspective of a bowling score cabinet showing my new design, the dominant features of the design being shown in full lines; and

Fig. 2 is a side elevational view of the same, the opposite side of the cabinet being substantially the same and the rear thereof being substantially plain.

I claim:

The ornamental design for a bowling score cabinet, as shown and described.
